UNITED STATES PATENT OFFICE.

WILLIAM OVIL BOWMAN, OF FAIRFIELD, CALIFORNIA, ASSIGNOR, BY DIRECT AND MESNE ASSIGNMENTS, TO THE UNIVERSAL IRONING BOARD COMPANY OF SAN FRANCISCO, CALIFORNIA.

IRONING-BOARD.

SPECIFICATION forming part of Letters Patent No. 653,839, dated July 17, 1900.

Application filed April 2, 1900. Serial No. 11,040. (No model.)

To all whom it may concern:

Be it known that I, WILLIAM OVIL BOWMAN, a citizen of the United States, residing at Fairfield, in the county of Solano and State 5 of California, have invented new and useful Improvements in Ironing- Boards, of which the following is a specification.

My invention relates to improvements in ironing-boards, the object of my invention 10 being to provide a device of this character which can be readily attached to the edge of any table or similar support, which attachment, while very simple and easy, shall yet connect the ironing-board with the edge of 15 the table very firmly and hold the board very securely against lateral movement, and one, moreover, which shall permit of a number of boards of different sizes being used in conjunction with the same standard, so that at 20 very slight expense there is provided a complete set of ironing-boards of different sizes for different purposes, all in connection with the same standard.

My invention therefore resides in the novel 25 construction, combination, and arrangement of parts for the above ends hereinafter fully specified, and particularly pointed out in the claim.

In the accompanying drawings, Figure 1 is 30 a perspective view of the device in position, clamped to an end of a table. Fig. 2 is a perspective view of a set of three boards of different sizes which may be used in conjunction with the same standard. Fig. 3 is an 35 under view of one of the boards. Fig. 4 is a longitudinal central section of the same. Fig. 5 is a side elevation of a standard, and Fig. 6 is a vertical section through the board, standard, and table near the point of support.

Referring to the drawings, *a* represents an ironing-board, having at its inner end *b* a central longitudinal slot or recess *c*. Said inner end *b* is adapted to be passed under the edge *d* of a table or other similar support, and 45 in said slot is received the upper end of a standard *e*, said upper end being notched in its lower edge, as shown at *f*, said notched portion resting upon the upper surface of the edge *d* of said table. Across the board on its 50 under side, in front of the inner end of the

slot *c*, is secured a cleat *g*. Said cleat rests upon the notched portion *h* in the upper edge of the upper end of the standard *e*. The front edge of the cleat *g* is made square with the board to fit against the vertical face of the 55 notch *h*, while the end of the recess *c* is made beveled, as shown at *s*, to rest upon the upper sloping edge of the standard. The object of providing said cleat *g* on the under side of the board *a* is threefold: 60

First. It prevents the board from warping, to which there is great tendency in an ironing-board on account of the unequal temperature to which the different parts of the board are exposed. 65

Secondly. It prevents the board splitting in a line with the edge of the slot *c*. There is great danger of this on account of the support of the board being wholly underneath the narrow central portion of the board which 70 is in line with said slot, whereas the pressure of the board is very often on the sides. 75

Thirdly. The cleat has a central recess *k*, as shown in Fig. 3, which recess fits around the standard *e*, and thus the cleat serves to hold the board on said standard against side motion. For the same purpose also there are provided on the upper side of the board two cleats *l* in line with one another on opposite sides of the slot *c*. The inner ends of these 80 cleats abut against the sides of the standard *e*, which extend above the board. The sides of the cleats *l* will also abut against the edge of the table, and thus furnish additional means for preventing side movement of the 85 board.

By giving suitable dimensions to the parts the same standard *e* may be used with a complete set of boards. Thus in Fig. 2 are shown three boards of different sizes for different 90 purposes—as, for instance, ironing ladies' skirts, children's skirts, and sleeves of garments; yet any one of these boards may be used with the same standard *e*, for the width of the slot *c* is the same in all the boards and 95 so is the combined thickness of the cleat *g* and the inner end *b* of the board.

I claim—

In an ironing-board, the combination with the standard having notches in its upper and 100

lower edges, of the ironing-board having a longitudinal slot or recess in its inner end, and having a cleat secured on its under side across the board at the inner end of said slot, 5 said cleat resting in the notch in the upper edge of the standard and being centrally recessed to fit snugly around the standard, said board having also cleats secured on its upper surface in line with each other on opposite 10 sides of the slot, the inner ends of said latter

cleats being in position to abut against the sides of the standard extending above the board, substantially as described.

In witness whereof I have hereunto set my hand in the presence of two subscribing wit- 15 nesses.

WILLIAM OVL BOWMAN.
